JOINT FILLING MACHINE FOR BITUMEN
FILLER

Amasa E. Stewart, Utica, N. Y.

Application November 23, 1937, Serial No. 176,107

3 Claims. (Cl. 94—39)

This invention relates to a machine for filling with bitumen the joints in concrete or similar pavements and for marking a traffic line.

The general purpose of my present invention is to provide a machine of the sort indicated which is of new and improved construction, simple and economical to make and to keep in repair, and which can be easily and efficiently operated under various road conditions and which is of such construction and combination of its parts that the machine is easily and accurately steered and controlled to keep the supply of bitumen directed to the joint in the proper variable amount and to the uniform width required and with regularity and neatness.

A further purpose is to provide a machine of the character indicated wherein rubber composition shoes or guards to limit the ribbon of bitumen are so placed, supported and resiliently pressed towards the pavement as to make close contact therewith without vibration and with a minimum of friction and wear and so that the ribbon of bitumen filling will not have to be retouched by hand work.

A further purpose is to provide a machine of the character described of the type which is towed by outside power as by a truck travelling ahead of this machine and of a sort where the machine is provided with hot bitumen through a flexible tube extending forward conveniently to a heating tank containing the supply of bitumen filling. With the machine being so towed and supplied with the hot bitumen from a source of supply not upon the machine itself, I am enabled to make the machine relatively small and light in weight and very low down or close to the pavement and with every facility for accurately and easily applying the bitumen to the joint in the pavement. Particularly the machine is constructed so that the operator riding upon a machine has a clear and unobstructed view of the joint for some distance ahead of the nozzle and immediately at the nozzle so that he can both keep the nozzle over the joint and regulate the supply of filling according to the size of the joint to be filled. The steering wheels of the carriage are very close to the transverse line of the nozzle towards the front of the machine so that the nozzle which is relatively fixed upon the carriage can be at all times kept directly over the joint.

A still further purpose is to provide a machine of this type which has combined therewith particularly effective and convenient guards or shoes for properly locating the bitumen filler and

for preventing the wind from diverting or disturbing the poured stream of liquid bitumen.

Further purposes and advantages of the invention will appear from the specification and claims herein.

Fig. 1 is a plan view of a machine embodying this invention.

Fig. 2 is a vertical longitudinal sectional view substantially along the center line of the machine but showing parts at or near the center in side elevation.

Fig. 3 is a vertical sectional view on line 3—3 when the two strips of pavement are on different levels.

Fig. 4 is a plan view on an enlarged scale of the two guards or shoes 35 and the adjacent ends of their supports and the lower part of the nozzle equipped with a brush for adapting the machine to make a wider marking ribbon of bitumen.

Fig. 5 is a vertical elevation on line 5—5 of Fig. 4.

Referring to the drawing in a more particular description, it will be seen that the machine in question comprises a wheeled carriage 10, a nozzle 11 mounted thereon connected through a valve 12 to a flexible hose 13 which is of a character and length to be connected to a tank of heated bitumen carried conveniently slightly in advance of this machine as upon an automobile, which automobile also provides the power for towing the joint filling machine.

The wheeled carriage 10 may conveniently include two spaced longitudinally extending side members 14 such as lengths of angle iron of proper size and strength and several cross boards 15 secured about midway the length of the carriage to the horizontal webs of the angle iron side members 14 and forming the platform of the carriage. To this platform is secured the lower end of a slightly resilient seat support 16 which at its upper end carries the seat 17 for the use of the operator of the machine.

Near its rear end a transversely extending rear axle 18 suitably mounted upon the side members 14 carries at its projecting opposite ends relatively small wheels 19 preferably equipped with pneumatic tires 20. At its forward end the carriage is provided with a pair of steering wheels 21 respectively mounted upon outwardly extending spindles 22 each one of which is one arm of a bell crank pivoted as at 23 upon the opposite side members 14. The other arm 22' of each bell crank extends rearwardly for a short distance and is there pivotally connected to the

connecting rod 24. One of these rearwardly extending arms, say the right hand arm is extended rearwardly as a steering lever 25 the rear end of which is brought to the proper height 5 and close enough to the operator seated upon the carriage for the said operator to easily and accurately steer the machine by swinging said steering arm to the right or left as required to keep the nozzle 11 directly over the joint in the 10 pavement.

At the front of the carriage there is provided a strong U-shaped yoke 26 having the rear end of each arm rigidly connected to one of the opposite side members 14 at the front thereof. 15 The central portion of this yoke is raised somewhat above the level of the frame of the carriage and is also conveniently slightly in advance of the front end of the side members and provides at the center line of the carriage a support 27 in which is securely but preferably adjustably mounted the upper end of the nozzle 11 as by clamp 27'. This nozzle as best appears in Fig. 2 extends sharply downwardly and slopes slightly to the rear and its lower or outlet end 20 is slightly above the level of the pavement, the joint of which is to be filled by the bitumen filling flowing from said nozzle. From the middle of the yoke 26 below the nozzle support 27 there may be provided a tow eye 28 for the attachment of the rear end of the tow rope or line 25 going forward to the truck which is to tow this machine. It will be understood that once the nozzle 11 is set to the proper position in the machine as to height above the road and angle thereto, it will not need to be adjusted while the machine is in operation. On the other hand the supply of bitumen filling fed through the nozzle 11 may need to be constantly varied according to the width of the joint between the 30 slabs of concrete or other parts of the pavement being treated and according also to the depth of the opening in the joint and according somewhat to the extent to which the bitumen filling is to rise above the top level of the pavement or 35 crown over the joint and also of course to the width of the ribbon of bitumen filling that the machine is set to provide.

The movable member 29 of the valve 12 is conveniently and preferably a simple plunger longitudinally movable through a passage 30 which is at right angles to the bore 31 of the valve so that longitudinal movement of the movable part 29 in an obvious manner directly opens or closes the said valve quickly and positively. To the 40 outer end of the valve member 29 there is pivotally connected the forward end of a long connecting rod 32 the rear end of which is in turn pivotally connected to the valve lever 33. This valve lever has its lower end pivotally supported 45 in suitable bracket 34 provided on the front cross board 15 and said lever projects upwardly above its connection to the rod 32 to a proper distance to have its upper end readily reached and moved backward and forward by the operator who is seated upon the carriage of the machine.

Adjacent the lower part of the nozzle 11 there are provided and resiliently mounted relative to the carriage of the machine two oppositely placed spaced shoes or guards 35. As best appears in 50 Fig. 1 each of these guards is concave on its inner face that is, its face towards the nozzle so that both the forward end and the rear end of each shoe is considerably closer to the center line of the machine than is the central part of that shoe. 55 I have found that the most efficient material for

the shoe is a rubber composition, that is, a rubber with fiber or fabric reinforcement such as is provided by slitting the shoe of an ordinary automobile tire to provide pieces of the shape and relative size as shown in Figs. 1 and 2, the wire reinforced portions of said automobile shoes being first eliminated. A length of fabric or fiber reinforced rubber belting of sufficient thickness is another possible form of shoe for the machine. Ultimately specially built fiber reinforced or rubber composition shoes may be specially provided of the size and character required for this particular machine. The rubber composition herein suggested has sufficient strength and durability to stand the wear of being pushed with sufficient tension against the upper surface of the pavement over which the machine is being drawn. The right hand shoe 35 is removably secured as by bolts and nuts 36 to the left hand or inner side of the vertically arranged forward end 37 of the right hand shoe support 38. Preferably the body of this shoe support is a strip of resilient metal of sufficient strength and resilience to hold the lower end of its shoe 35 down against the top surface of the pavement. 20 Preferably the forward end of this strip of metal is bent to be vertically arranged and curved concave at its inner side to receive the curving shoe 35 but immediately to the rear of this vertical portion the shoe support 38 has the width of its 25 metal extending horizontally or crosswise of the machine so as to utilize the resilience of the metal. A convenient way of mounting this shoe support is to have its extreme rearward end permanently fastened as by rivets or bolts 39 to the rearward underside of a heavy sheet metal cross piece 40 rigidly attached at its opposite ends to the lower surface of the horizontal webs of the angle iron side members 14 of the carriage. Forward of the front bolt 39 the right hand support 38 is engaged by the lower end of a bolt 41 the shank of which is screw-threaded perpendicularly in said metal cross member 40 with the head of said bolt thereabove so as to be readily reachable with a wrench or other tool. By 30 screwing this bolt 41 downwardly it will be obvious that the forward end of this spring arm 38 is forced downwardly with greater tension against the pavement. The left hand shoe 35 is similarly mounted upon its own separate left hand shoe support 42 which is of resilient metal similar to support 38 and which is similarly mounted upon the cross member 40 and similarly tensioned by its own separate adjusting bolt 43. In an obvious manner also these adjusting bolts 35 41 and 43 may be used to take up and to a certain extent extend the wear upon the bottom of the shoes 35. I have found by careful experiments and actual experience that these rubber composition shoes or guards 35 when carried 40 near the front end of the machine and at the front end of forwardly extending spring arms will not vibrate or jump up and down relative to the pavement but will follow along closely scraping the pavement with sufficient tension 45 and sufficient regularity to insure a uniform width to the ribbon of bitumen according to the distance the shoes are set apart. It will be noted particularly that each shoe is entirely independent of the other so that each shoe may spring 50 up and down to adjust itself to different elevations of the slab of pavement on the opposite sides of the joint being treated. This individual adjustment of the two shoes is sufficient to keep each shoe in contact with the pavement even 55

though one slab at one side of the joint is considerably above the other and so moves the steering wheel at that side of the joint proportionately upward. The length and resiliency of the 5 shoe carrying arms 38 and 42 is sufficient to give the required independent action for each shoe. It will also be understood that the rubber composition of the shoes also helps in keeping the shoes regularly against the pavement in that the front 10 end of the shoes can slightly bend or buckle when they come to a transverse inequality in the pavement, but that the shoes will not be permanently distorted and will not spring above such local obstacle enough to make the ribbon of 15 bitumen irregular in width.

It will be noted further that the steering wheels are very close to the transverse line where the nozzle 11 directs the supply of bitumen so that the operator of the machine by relatively 20 slight movement of the steering lever is at all times able to keep the nozzle right over the joint being treated. It will be further seen from inspecting the drawing that an operator upon the seat 17 of the carriage will have a clear view looking 25 downwardly and forwardly to the opening of the joint ahead of the nozzle and particularly to the joint just at the rear of the nozzle to which the hot bitumen has just been supplied so that the operator can be thus guided as to steering 30 the machine and also as to the amount of liquid bitumen to be supplied at any particular length of the joint. It will be seen that the whole machine is purposely designed so that the operator can keep his eye upon the pouring point, that 35 is the outlet of the nozzle and with one hand steer the machine as needed and with the other hand can instantly and constantly control the supply of bitumen coming through the valve 12 to the nozzle. In this machine it will be particularly 40 noticed that the operator does not have the tiring work of wheeling the machine itself along the pavement and up hill and down grades. Nor does the operator of this machine have to attend to any mechanism as to the main supply 45 of bitumen nor the heating thereof. The only other mechanical device on this machine is a brake 44 applied to a drum upon one of the rear wheels and controlled by a member 45 going forward to a brake lever 46 having a pedal 47 at its 50 forward end within convenient reach of one foot of the operator of the machine.

After considerable experiments I have found that the flexible hose 13 bringing the hot bitumen to the nozzle needs to be of the spirally wound 55 metal type rather than ordinary rubber or rubber lined hose because the hot bitumen tends to quickly deteriorate the rubber of the rubber hose and dislodge portions of such rubber hose and carry it into the valve of the machine where it 60 blocks the supply of bitumen and results in disastrous delay and waste of time in the use of the machine.

It will be understood that the shoes 35 are readily removable from their supporting bars and 65 that new or other shoes may be quickly attached to said supports. On account of the hard service the shoes have to stand the shoes wear out or wear down too much to be used after the set has been used for one hundred to one hundred and 70 fifty miles of pavement. In practice I have found that this machine can be drawn and work entirely satisfactory at the rate of about three to four miles an hour.

This machine as ordinarily used leaves a ribbon 75 of bitumen centered along the longitudinal joint

of a pavement which ribbon being black forms a convenient marker indicating the center line of a two track highway. If it is desired this black ribbon can purposely be made more prominent by making it wider than is necessary simply for a 5 joint filler. Figs. 4 and 5 are two views showing one form of a modification adapting this machine to make such a wider ribbon of bitumen. A sufficiently flexible brush 48 is mounted to the rear of the nozzle 11 as by the handle 49 of the brush 10 being removably and adjustably secured as by clamp 50 and conventional bolts and nuts to the nozzle 11. Usually when the machine is being operated to make a prominent marking ribbon, the guards 35 will be set a little farther apart 15 than they are placed for only filling the joint so that the bitumen when spread out by the brush, which may be say two and one-half inches in width, will reach the adjacent portion of the guards on each side to cover the pavement for, 20 say, a four inch ribbon. Some of the bitumen will flow out beyond the edges of the brush and some of this will be pushed back towards the center by the rear inwardly slanting ends of the opposite guards but the pavement once reached 25 by the bitumen will remain black.

What I claim as new and desire to secure by Letters Patent is:

1. In a joint filling machine for bitumen filler, the combination of a low-down wheeled carriage 30 having steering wheels near its forward end manually controlled relative to the carriage by an operator on the carriage, a nozzle rigidly mounted near the forward end of the carriage and adapted to direct a bitumen filler downwardly upon a 35 joint in the pavement below the carriage, connections including a manually controlled valve leading from the nozzle to a source of supply of bitumen, means operable by a person on the carriage to regulate said valve, fabric-reinforced, elastic 40 composition shoe-guards of the stiffness and durability of the shoe or casing of automobile tires, spaced apart the desired width of the strip of bitumen filler and on the opposite sides of the nozzle outlet and allowing the strip of filler over 45 the joint and for some distance laterally thereof to pass rearwardly between the opening at the rear ends of said shoe-guards without being engaged by said shoes and two separate, resilient horizontally arranged supports mounted at their 50 rear ends about a third of the way back on said carriage and extending forward to the line of said nozzle and there carrying respectively one of said shoe-guards and resiliently pressing them 55 strongly enough against the pavement to prevent the filler from spreading laterally across the pavement beneath said shoes.

2. In a joint filling machine for bitumen filler, the combination of a low-down wheeled carriage 60 having steering wheels near its forward end manually controlled relative to the carriage by an operator on the carriage, a nozzle rigidly mounted near the forward end of the carriage and adapted to direct a bitumen filler downwardly upon a joint in the pavement below the carriage, connections including a manually controlled valve leading from the nozzle to a source of supply of bitumen, means operable by a person on the carriage to regulate said valve, fabric-reinforced, elastic composition shoe-guards of the stiffness and durability of the shoe or casing of automobile tires, spaced apart the desired width 65 of the strip of bitumen filler and on the opposite sides of the nozzle outlet, and allowing the strip 70 of the nozzle outlet, and allowing the strip 75

of filler over the joint and for some distance laterally thereof to pass rearwardly between the opening at the rear ends of said shoe-guards without being engaged by sail shoes and two separate, resilient horizontally arranged supports mounted at their rear ends about a third of the way back on said carriage and extending forward to the line of said nozzle and there carrying respectively one of said shoe-guards and resiliently pressing them strongly enough against the pavement to prevent the filler from spreading laterally across the pavement beneath said shoes, said shoe-guards being readily detachable from and attachable to their supports, and means 10 on said carriage engaging the rearward parts of said supports for adjusting vertically and separately their forward ends to compensate for the wearing away of the lower edges of said shoes, such adjustment not interfering with the resiliency of said supports.

3. In a joint filling machine for bitumen filler the combination of a towed, low-down four-wheeled carriage having two steering wheels near its forward end manually controlled relative to the carriage by an operator riding on the rear part of the carriage, a nozzle rigidly mounted near

the forward end of the carriage and adapted to direct a bitumen filler downwardly on a joint in the pavement below the carriage, connections including a manually controlled valve leading from the nozzle to a source of supply of bitumen off of the carriage, means operable by said person on the carriage to regulate said valve, fabric-reinforced, elastic composition shoe-guards of the stiffness and durability of the shoe or casing of automobile tires, spaced apart the desired width 10 of the strip of bitumen filler and on the opposite sides of the nozzle outlet, and allowing the strip of filler over the joint and for some distance laterally thereof to pass rearwardly between the opening at the rear ends of said shoe-guards 15 without being engaged by said shoes and two separate resilient horizontally arranged supports mounted at their rear ends about a third of the way back on said carriage and extending forwardly to the line of said nozzle and there carrying respectively one of said shoe-guards and resiliently pressing them strongly enough against the pavement to prevent the filler from spreading laterally beneath said shoes.
